CLOCK

Charles Richard Maddox, Beverly Hills, Calif.

Application July 24, 1956, Serial No. 42,363

Term of patent 14 years

(Cl. D42—7)

I claim:

The ornamental design for a clock, substantially as shown.
